C. C. HUBBELL

HAIR CURLING DEVICE

Filed Jan. 3, 1925

UNITED STATES PATENT OFFICE.

CHARLES C. HUBBELL, OF PITTSBURGH, PENNSYLVANIA.

HAIR-CURLING DEVICE.

Application filed January 3, 1925. Serial No. 324.

This invention relates to hair curling devices and more particularly to electrically operated curling devices adapted for producing in human hair so called permanent waving.

One of the principal objects of this invention is to provide a curling device in which the possibility of burning out the electric heating wires, due to the operator's negligence, is practically eliminated. Another object is to provide an apparatus of this character in which the hair may be kept under a regulated tension during the so-called baking process, for the purpose of expediting the operation and producing a more lasting wave-effect. A further object is to provide a curling device in which the heat and steam generated during the baking process are carried away from the scalp of the patient, thereby greatly adding to the latter's comfort. Still another object is to provide a simple device of relatively low cost of manufacture having simple means for quickly gripping the tuft of hair which is about to be curled and for holding said tuft with increasing pressure as it is directed toward a central curling barrel, forming part of the device. Additional features and advantages of this invention will appear from the following description considered in connection with the appended drawing forming a part of this application. The purpose of this application is especially to cover certain new improvements not shown in a now pending application for Letters Patent on the same subject matter, filed September 8, 1924, and bearing the Serial Number 736,509.

In the drawing:

Fig. 1 is a general longitudinal section through the curling device.

Fig. 2 is a section taken substantially on line 2—2, Fig. 1, and showing diagrammatically the connections for the electric heating wire.

Fig. 3 is a cross-section taken substantially on line 3—3 in Fig. 1.

Fig. 4 is a front end view of the heating barrel of the curling device.

Fig. 5 is an enlarged view, mostly in section, showing the complete curling element of the device and a fragmentary part of the heating element.

Fig. 6 is a view of the front end of the curling barrel of the device. 55

Fig. 7 is a front elevation of the hair gripping element.

Fig. 8 is a side elevation of Fig. 7.

Fig. 9 is a front elevation of an intermediate member of the gripping element. 60

Fig. 10 shows the inner member of said hair gripping element.

Fig. 11 is a front elevation of the gripping wheel of the gripping element.

Fig. 12 is a general view showing the device as applied. 65

Fig. 13 is a perspective view of a connector used in the device.

Reference being had to the drawing, my hair-curling device comprises two principal parts, namely, the heating element H and the curling-element C. The former is composed of a metal tube 1 secured at the forward and the rear end in the collars 2 and 3 respectively, made of thermo-electric insulating material. This tube is covered intermediate said collars with a layer of mica 4 upon which a coil of electrical heating wire 5 is wound, through which a current of electricity may be circulated. This heating wire is protected outwardly with a covering 6, preferably of asbestos, for the purpose of reducing the loss of heat through radiation to the outside. The collars and correlated parts are assembled within a sleeve 7 of insulating material of such inside diameter as to leave an air space 8, to reduce the heating of said sleeve. A suitable number of apertures 9 are provided in the latter to enable the escape of heated air from, and the entrance of cold air into, said space. 75

Diametrically disposed on the collar 3 are the inwardly directed switch-clips 16 and 17 made of resilient metal and secured by means of screws 18. These clips are provided at their inner ends with arcuate contact surfaces 19, for a purpose to be explained later. 85

Laterally secured in suitable grooves on said collar, and at right angles to the switch-clips are the connectors 82 and 83 made of metal and each provided with an inward hook portion 84 engaging the inner face of the collar. Said connectors are slightly bent toward the center of the heating element. 90 100 105

and are each provided adjacent their outer ends with a transverse slot 85. An aperture 86 is also shown in each connector to receive a screw 87 by means of which the collar and connector are securely held to the sleeve member 7.

As shown diagrammatically in Fig. 2, the switch-clip 16 and the connector 83 are electrically connected by means of a wire 20, 10 and the ends 21 and 22 of the heating coil 5 are respectively connected to the connector 82 and the switch-clip 17.

The rear end of the heating element is also provided with a removable cap 23 of 15 insulating material, having a central aperture 24 for slidably receiving and guiding the flexible electric cable 14, and a series of concentrically disposed holes 25 which facilitate the escape of heat and steam away 20 from the person undergoing the hair-curling process. On the inner face of this cap are moulded, or otherwise secured, the two bosses 26 and 27 upon which are mounted by means of the terminal screws 10, 11 and the 25 smaller holding screws 15 the connecting plates 88 and 89 having outwardly directed fingers 90 which are adapted to engage the oppositely directed slots 85 of the connectors. As shown especially in Figs. 2 and 30 13, the connecting plates are connected to the wires 12 and 13 of the cable 14 and are preferably supplied with two sets of oppositely bent lugs 91 and 92, the former embracing the bosses 26 and 27 to secure the 35 plates more positively thereon, and the latter acting as guides for the wires 12 and 13. The cap 23 is secured to the heating element by first slipping it over the sleeve 7 and then giving it a slight twist in the right direction 40 to cause the fingers 90 to enter the slots 85 in the connectors, thereby establishing an electrical connection between the wires 12, 13 and the heating coil 5, while at the same time also securely retaining the cap on the 45 heating element.

The front collar 2 is flush with the front end of the sleeve 7 and is counterbored at the front end to provide an annular seat 28 for the sealing washer 29. The latter is 50 made of a suitable heat resisting and compressible material, such as cork, to afford a substantially leak proof engagement between the heating element and the gripping element.

55 Said collar is also provided outwardly with two longitudinal grooves 30 in which are secured by means of screws 31 the hook-members 32 by means of which the hair gripping element may be clamped tight 60 against the front end of the heating element, in a manner to be described later.

The curling element C comprises a curling barrel 33 made up of two pieces of metal tubing 34 and 35 of suitable length, joined 65 together in axial alignment by the telescopic

ing sleeve connection indicated by the numeral 36. The forward end of the tube 34 is slightly tapered outwardly and is counterbored to a suitable depth to securely hold the cylindrical curling-shank 37 which is 70 preferably provided with slight knurls 38 to insure a better engagement in said tube. The forward end of said shank is slotted to form two resilient fingers 39 which are each provided at the forward end with the flat 75 portions 40 and the beads 41.

On the rear end of the tube 35 are cut a series of notches 42, of right-angled triangular shape, which are engaged by correspondingly shaped teeth 42 provided in the hub 43 of the flange 44, the whole forming a ratchet connection allowing the rotation of the said engaged parts in one direction only.

Placed within the curling barrel is a 85 spindle 45 having at the rear end a short threaded stud 46 screwed into the flange 44, a body portion 47 fitting snugly in a bushing 48, inserted in the hub 43, and in the tube 34. The forward end of said spindle is also threaded to accommodate a cylindrical nut 49 placed within the counterbored portion of the tube 34 and by means of which the latter is kept in proper, rotatable, engagement with the tube 35. Surrounding the spindle is a coil spring 50, the forward end 51 of which engages the reduced portion 52 of the tube 34 and is secured thereto in any desired manner, while the rear end of said spring is inserted into a hole 53 drilled into the spindle.

Secured to the flange 44, by means of rivets 54, is the disc-centralizer 55, made of electric insulating material. This disc is preferably knurled and is made slightly smaller than the inside diameter of said sleeve and has a central aperture 56 suitably threaded to receive the short threaded stud 57 of the switch-plug 58, the end of which is preferably tapered to facilitate its insertion between the contact surfaces of the switch-clips 16 and 17. The stud 57 is made shorter than the thickness of the disc 55 to prevent any electrical connection between the switch-plug and the other metallic parts 110 of the curling element.

The hair-gripping element, which also acts as a head-protector against the heat generated within the curling device, is composed of the outer disc 59, the intermediate disc 60 and the inner disc 61, all three discs being properly held together by means of rivets 62 and a pivot-pin 63 upon which is rotatably mounted the hair-gripping wheel 64, positioned intermediate the outer and inner discs in a circular recess 65 cut in the intermediate disc 60.

In the outer disc 59 and the inner disc 61 are cut respectively the curved open slots 66 and 67 of suitable width and concentrically 130

disposed around the pivot-pin 63. These slots are so arranged as to register with an arcuate recess 68 cut in the periphery of the gripping wheel, when the latter is properly 5 rotated.

The inner disc has two diametrically disposed recesses 69 cut in its periphery to allow for the passage of the bent portion 70 of the hook-member 32. A rectangular central aperture 71 is also provided to snugly receive the flattened portions 40 of the curling-shank which may be snapped into said aperture owing to the resiliency of the fingers 39.

15 In the intermediate disc are also cut two arcuate slots 72 and 73 disposed concentrically and diametrically opposite, and of sufficient width to permit the insertion therein of the bent portion of the hook-member.

20 The length of these slots is such as to permit a sufficient rotation of the whole gripping member to enable the bent portion of the hooked member to fully engage the periphery of the inner disc, thereby holding 25 said gripping member against the sealing washer 29 at the forward end of the heating element. At the center of the intermediate member is also provided a rectangular aperture 74 which registers with the similar aperture 71 in the inner disc, but which is made longer in order to provide ample room for the beads 41 on the curling shank, and to enable the resilient fingers thereof to assume their normal position after insertion 30 through the inner disc, thereby forming a good snap-connection between the curling element and the hair-gripping element.

A feather-spring 75 is secured in the slot 76 provided in the intermediate disc to operate 40 against the knurled periphery of the gripping wheel to hold the latter in any selected position.

The curling device is applied by an operator in the following manner:—

45 A tuft of hair of suitable size is first laid into the recess 68 of the gripping-wheel held close to the scalp, and the former is then turned by the operator to gather the tuft in the curved slots 66 and 67 and grip it firmly

50 as it approaches the center of the gripping-member. The curling element is then snapped into the central aperture of the gripping-member and the tuft of hair is wrapped around the curling element in a clock-wise sense (as seen by the operator and if the ratchet teeth are as shown in the drawing) and the free end of the tuft is tied to the curling element by means of a string. The coiled tuft is now enclosed in a strip of 55 damp cloth, such as flannel, which is wrapped around in the same sense as the hair. When so arranged, the coiled hair is put under additional tension by rotating the disc-centralizer in a counter-clock sense, while the tubes

60 34 and 35 of the curling barrel are held 65 against rotation by pressing with the fingers of the other hand at the place of junction 36 of said tubes. When the desired tension is obtained, the hold at the junction is released, the result being that the tube 35, under the 70 action of the stressed coil-spring 50, will exert a constant tension on the coiled tuft of hair in the same direction in which the latter was wound.

75 The heating element H, which is connected to a source of electric energy by means of a line-plug 77, is pushed over the curling element until the bent portions of the hook-members 32 enter the recesses 69 provided in the gripping-element. The heating element "H" is then given a slight twist to cause the hook-elements to securely hold the gripping-member against the sealing-washer 29, thereby preventing the escape of steam 80 against the scalp. By so doing, the switch-plug 58 is forced between the contact surfaces of the switch-clips 16 and 17 and a closed circuit for the passage of electric current in the heating-coil is established, as will be readily understood by referring to 85 Fig. 2.

90 As the process of baking lasts several minutes, and in order to save time, the complete device, when applied, is suspended by means of a suspension ring 78 slidably engaging the outer sleeve 7 and fastened to a cord 79 passed over a pulley 80 and having a counter-weight 81 tied at the other end. While the baking-process is going on, one or more tufts of hair may be prepared on additional curling elements, as suggested in 95 Fig. 12.

100 Upon completion of the baking process, the operator removes the heating element by first twisting it to disengage the hook-members from the gripping-member and then pulling it away from the curling-member, thereby breaking the engagement of the contact-plug with the switch-clips. The electric current 105 within the heating wire is therefore interrupted and all danger of burning said wire, due to the operator forgetting to turn off the electric current at the line switch, is eliminated.

110 As will be understood, there may be slight changes made in the construction and arrangement of the details of my invention without departing from the field and scope of the same, and I intend to include all such variations, as fall within the scope of the 115 appended claims, in this application, in which the preferred form only of my invention has been disclosed.

I claim:

1. In a hair curling device of the character 125 described, the combination of an electrically operated heating element; a curling element insertable therein and a hair gripping element removably securable to said heating element and said curling element; said hair 130

gripping element comprising two concentric outer disc-members, an intermediate disc-member and a hair gripping wheel rotatably mounted eccentrically of and between said outer disc-members; said gripping wheel having a peripheral recess adapted to receive a tuft of hair, and said outer disc-members having each a curved slot disposed concentrically with said gripping wheel and adapted to register simultaneously with said recess.

2. In a hair curling device of the character described, the combination of an electrically operated heating element; a curling element insertable therein and a hair gripping element removably securable to said heating

element and said curling element; said hair gripping element comprising two concentric outer disc-members, an intermediate disc-member and a hair gripping wheel rotatably mounted eccentrically of and between said outer disc-members; said gripping wheel having a peripheral recess adapted to receive a tuft of hair, and said outer disc-members having each a curved slot disposed concentrically with said gripping wheel and adapted to register simultaneously with said recess, and yielding means to hold said gripping wheel in any selected position.
